United States Patent Office

Des. 215,405
Patented Sept. 30, 1969

215,405

CLEAT

Henry A. Patnaude, 531 Los Molinos Way,
Sacramento, Calif. 95825

Filed Oct. 25, 1968, Ser. No. 14,174

Term of patent 14 years

Int. Cl. D8—03

U.S. Cl. D8—232

FIG. 1

FIG. 4

FIG. 5

FIG. 2

FIG. 3

FIGURE 1 is a side perspective view of a cleat showing my new design;

FIGURE 2 is a front elevational view thereof;

FIGURE 3 is a rear elevational view thereof;

FIGURE 4 is a side elevational view thereof; and

FIGURE 5 is a top view thereof.

I claim:

The ornamental design for a cleat, substantially as shown.
